[57] CLAIM

The ornamental design for a seed packet holder, as shown and described.

DESCRIPTION

FIG. 1 is a front elevational view of a seed packet holder showing my new design;

FIG. 2 is a rear elevational view thereof;

FIG. 3 is a left side elevational view thereof, the right side being a mirror image of that shown;

FIG. 4 is a vertical cross-sectional view thereof, taken along line 4—4 of FIG. 2;

FIG. 5 is a top plan view thereof; and,

FIG. 6 is a bottom plan view thereof.
